UNITED STATES PATENT OFFICE.

ROBERT HARDIE, OF BROOKLYN, NEW YORK, ASSIGNOR TO HENRY C. ELLIOT, OF NEW YORK, N. Y.

CIGARETTE-CUTTING DEVICE FOR CONTINUOUS-CIGARETTE MACHINES.

SPECIFICATION forming part of Letters Patent No. 558,646, dated April 21, 1896.

Application filed May 17, 1895. Serial No. 549,645. (No model.)

To all whom it may concern:

Be it known that I, ROBERT HARDIE, of Brooklyn, in the county of Kings and State of New York, have invented a certain new and 5 useful Improvement in Cigarette-Cutting Devices for Continuous-Cigarette Machines, of which the following is a specification.

My invention relates to improvements in those devices which are used in machines automatically forming a continuous cigarette or a filler-rod inclosed by a paper wrapper to divide up the cigarette as it issues from the machine into appropriate lengths.

I will describe a cutting-off device for a continuous-cigarette machine in which are embodied the features of my invention, and then point out its novelty in the claims.

In the accompanying drawings, Figure 1 is a plan view of a cutter embodying my invention. Fig. 2 is an end view thereof. Fig. 3 is a longitudinal section on the plane of the line 3 3 in Fig. 1.

Similar letters of reference designate corresponding parts in all the figures.

25 As the present improvement is in no way dependent in its action upon the special form or construction of the cigarette-producing machine to which it is applied, but may be combined with any cigarette-machine which produces a continuous-tobacco-filler rod inclosed within a wrapper, (the so-called "continuous cigarette,") I have not deemed it necessary to illustrate such a machine, except so far as showing at A a portion of the framing of the 35 machine upon which the cutter is supported.

B is a plate secured to the framing A and having two tongue-pieces projecting from the main portion of the plate, to which tongue-pieces there are secured the blocks a and a', 40 respectively. Fitted to the V-block a and adapted to move lengthwise of the continuous cigarette to and fro is a sliding carriage C. Similarly C' is a carriage fitted to the V-block a'.

45 Each carriage C and C' carries a cutter, presently to be described, comprising a sharp-edged disk. The cutters are duplicates of each other, each being alternately out of action and then in action, in which event the 50 tobacco-filler rod inclosed by the paper wrapper, or, in other words, the continuous ciga-

rette, is severed. Each cutter has also during the act of cutting off a length from the continuous cigarette a simultaneous longitudinal movement with the latter.

55 After the length has been cut and the cutter has reached the limit of its simultaneous longitudinal movement with the onwardly-moving continuous cigarette issuing from the machine the former is withdrawn from the cutter, which thereupon returns to the opposite limit of movement, ready again to pass through the same series of motions.

I will now proceed to describe the construction which I prefer to employ to secure the 65 reciprocation of the carriages, as well as the action of other mechanisms by which the operation as described is brought about.

The plate B is provided at D with an extension, to which there is pivoted at d a double-armed lever E, whose ends are slotted and embrace studs e and e', extending from the carriages C and C', respectively.

70 F is a cam-shaft journaled in bearings secured to the framing of the machine. To it 75 there is affixed a cam F', against the periphery of which bear two cam-rollers f and f'. These cam-rollers f and f' are journaled to studs projecting from a sliding plate F², working in suitable guides to permit of this movement. The sliding plate F² imparts its motion to the lever E through a link F³, pivoted at one end to the lever and at the opposite end secured to the sliding plate in a manner to permit it to conform to the slight changes 80 in direction caused by the turning of the lever E on its center without cramping. As shown, this connection may comprise a forked end formed on the link, to which there is secured a cross-pin f³, the latter having a bearing in 85 the plate F².

It is evident from this construction that a rotation of the cam-shaft F will produce a vibration of the lever E, and consequently a reciprocation of the carriages C and C' in opposite directions.

To the carriage C there is secured a pedestal G and to the carriage C' a pedestal G'. A sharp-edged disk G², forming a cutting-disk, is secured to a shaft by suitable means, 100 the latter being journaled in pedestal G, while a similar disk G³ is similarly mounted in the

pedestal G'. These cutting-disks are rotated by a belt G⁴ driven by any suitable drum or pulley. (Not shown.) The cutting-disks will preferably be driven in opposite directions, and their motions at the adjacent portions of their peripheries will be downward.

H is the continuous cigarette formed by the machine, H' being a portion of the flexible belt common to this class of machines, from which the cigarette is withdrawn by the finger h. A V-shaped trough H² receives the continuous cigarette as delivered from the machine, it being carried by an arm h', extended from the framing of the machine.

15 A bent lever I is fulcrumed at the point i to a boss of the carriage C, while to the boss of the carriage C' there is fulcrumed at the point i' a similar lever I'. These levers consequently are carried bodily with their respective carriages during their movements. During the bodily movement of each lever in the reverse direction to that in which the cigarette is moving its upper extremity is depressed below the cigarette by means presently to be described. During a movement in the opposite direction, however, the lever is elevated and the cigarette seated on a supporting-piece and carried across the periphery of its respective disk. In the present instance the supporting-pieces are made in the form of plates, with their lower edges bent trough-shaped.

30 K designates the supporting-plate, secured in any suitable way to the upper extremity 35 of the lever I, while K' designates the corresponding supporting-plate of the lever I'.

For securing the movement of the bent lever I upon its fulcrum-points I provide an arm L, pivoted at the point l, whose upper 40 extremity is extended laterally to form a bearing-surface l', over which the lower extremity of the lever I slides as it is moved to and fro by the reciprocation of the carriage C. Preferably a friction-roller l² will be journaled to 45 the lever I and bear upon the surface l'.

Rigidly secured to the arm L is a dependent crank L', by the movement of which the arm L may be swung about its fulcrum-point.

M is an elbow-lever pivoted to a stud at m 50 and having at the extremity of one arm a pin m', bearing against a friction-roller l³, journaled to the lower portion of the crank L'. The remaining arm connects by a rod M' with a stud bearing a cam-roller m².

55 A cam is shown at M² affixed to the shaft F, against which the roller bears, and through the medium of which the lever L is operated to move the lever I upward. The cam-roller m² is hung from the framing of the machine 60 by a suspension-link f².

At O is shown a spring-tongue secured at one end to the table C, while at its upper portion it bears against a pin o, extending from the upper arm of the lever, when the upper 65 arm of the lever I is moved upward to lift the continuous cigarette from the bottom of the trough H². When the lever I moves down-

ward, the spring-tongue O in following the pin o to assume its normal position will press against the continuous cigarette and prevent its retaining its elevated position to the left. A helical spring O' may be used for returning the lever I to its lowermost position.

The construction for securing the necessary movements of the lever I' may be similar to 75 that already described, P being an arm pivoted at the point l and having a laterally-extending bearing-surface p, upon which a friction-roller p', supported on the lever I', rests.

R is an elbow-lever fulcrumed at r and 80 provided at one end with an upright pin r', which bears against a friction-roller p³, journaled at the lower portion of a crank P'. The lever R is vibrated through a rod R², pivoted at one end to one arm of the lever R, and at 85 the opposite end carrying a cam-roller r², bearing against the periphery of the cam M² under the influence of spring M³. The cam-roller r² may be supported from the framing of the machine by a suspension-link f³.

90 Springs S and S' are suitably positioned to perform functions already described as pertaining to the springs O and O'.

I may add that the extremities of the supporting-plates K and K', from which the continuous cigarette passes, are arranged very closely to their respective disks, so that when the continuous cigarette is carried up across the face of the disk to sever the same there will be a true shearing action and an absence 100 of bending action and consequent distortion.

105 I have shown a sharpening device for applying to each cutting-disk for keeping the same sharp. As the device for each disk is the same, when I describe the construction and position of its parts relatively to one disk it will equally apply to the other disk.

T is an arm extending from a shaft T', fitted to bearings on the carriage C. The arm supports a plate t, to which there is pivoted 110 at t' a block T². A fixed stud t² enters an aperture in the block T², it preferably being so secured therein as to be longitudinally adjustable. This adjustability may be secured by providing the block with a longitudinal 115 slot passing through into the aperture, a screw t³ entering a tapped hole in one of the side pieces of the slot to clamp the block upon the stud.

V is an emery or similar sharpening-wheel, 120 slightly conical, and mounted upon the stud t², its periphery bearing against the periphery of the corresponding disks. A cam-shaped piece v bears against the block T², it being rotated by a spindle v' to shift the emery-wheel from the surface of the cutting-disk. A spring v² is provided to move the emery-wheel toward the cutting device.

125 Preferably each pedestal G and G' will be so mounted as to permit the cutting-disks to 130 be moved toward and away from each other. This adjustability I may secure by providing each shaft T' with an arm V', having an arc-shaped slot v³, through which passes a bolt

^{v⁴}, whereby the pedestal may be adjusted to any position and clamped.

It will be seen that the stud ^{t²}, upon which the sharpening-wheel rotates, is inclined to the axis of the cutting-wheel, as seen in both the side and the end view of the machine. Such a mounting of the sharpening-disks, in addition to its conical form, will permit it to bear for approximately its entire width ⁵⁰ 10 periphery against the cutting-disk, while at the same time it will be slowly rotated on its axis during the rotation of the cutting-disk. These facts will preclude the formation of a shoulder or other configuration of the sharpening-wheel tending to destroy the cutting edge of the disk.

The operation of cutting off the appropriate lengths from the continuous cigarette may be described as follows: The continuous cigarette issuing from the machine passes through and out of the trough ^{H²}. Supposing now ²⁰ 20 the parts are in the position shown in the figures, in which the upper arm of the lever E is about to move toward the left, carrying the carriage C with it, the cigarette being lifted that the cutting-disk ^{G²} may sever it. The carriage C' simultaneously moves toward the right, the elbow-lever R being moved upon its pivot that the supporting-plate K' may be depressed in a manner already described to carry ²⁵ 30 it below the cigarette.

When the upper arm of the lever E has reached the limit of its movement to the left, the elbow-lever M depresses the supporting-plate K, the lever R elevates the supporting-plate K' and presses the continuous cigarette against the cutting-disk ^{G²} as the carriage C' is moved to the left to sever another length ³⁵ 40 from the continuous cigarette. These movements of the cutting-disks continue alternately throughout the operation of the device.

Having described my invention, what I consider as new, and desire to secure by Letters Patent, is—

45 1. The combination of longitudinally-reciprocating oppositely-mounted and oppositely-

moving cutters, the forward movement of each cutter corresponding to the forward movement of the cigarette issuing from a continuous-cigarette-forming machine, and ⁵⁰ 50 mechanism for causing a relative movement of the cigarette and one cutter toward each other while the cutter is moving forward, and then a relative movement of the cigarette and the other cutter toward each other, substantially as specified. ⁵⁵

2. The combination of longitudinally-reciprocating oppositely-mounted and oppositely-moving carriages, the forward movement of each carriage corresponding to the forward ⁶⁰ 60 movement of the cigarette issuing from a continuous-cigarette-forming machine, cutters mounted upon the carriages, mechanism for reciprocating the carriages, and mechanism for causing a relative movement of the cigarette and one cutter toward each other while the supporting-carriage is moving forward, and then a relative movement of the cigarette and the other cutter toward each other, substantially as specified. ⁶⁵ ⁷⁰

3. The combination of longitudinally-reciprocating oppositely-mounted and oppositely-moving carriages, the forward movement of each carriage corresponding to the forward movement of the cigarette issuing from a ⁷⁵ 75 continuous-cigarette-forming machine, cutters mounted upon the carriages, supporting-plates for the cigarette carried by the carriages, a lever for reciprocating the carriages and levers for causing a movement of first ⁸⁰ 80 one plate, with the cigarette, and then the other plate, toward its respective cutter, this movement corresponding with the forward movement of the respective carriage, substantially as specified. ⁸⁵

In testimony whereof I have signed my name to this specification in the presence of two subscribing witnesses.

ROBERT HARDIE.
